UNITED STATES PATENT OFFICE.

JEAN C. GREGORY, OF NEW YORK, N. Y.

FINGER-SHIELD.

1,257,846.

Specification of Letters Patent. Patented Feb. 26, 1918.

Application filed February 8, 1916. Serial No. 77,070.

To all whom it may concern:

Be it known that I, JEAN C. GREGORY, a citizen of the United States, residing at New York, in the county of New York and State 5 of New York, have invented new and useful Improvements in Finger-Shields, of which the following is a specification.

This invention relates to finger shields and is primarily adapted for use by typists or 10 others operating the keyboards of various machines.

An object of the invention is to provide a shield which may be readily fitted upon the finger of an operator and which shall be 15 provided with a tip of compressible material to absorb the shock and jar incident to the operation of the keyboard of a machine as well as to prevent the fingers from becoming sore or callosed or the breaking of the 20 nails from constant contact with the keys of the machine.

Another object of the invention is to provide a finger shield including a sleeve portion having its sides curved to conform to a 25 finger and provided with openings for the free circulation of air between the said sleeve and the finger of the operator and to further provide the sleeve with a removable tip of compressible material which may be 30 replaced when worn.

With the above and other objects in view, the improvement resides in the construction, combination and arrangement of parts set forth in the following specification and falling 35 within the scope of the appended claim.

In the drawing:

Figure 1 is a perspective view illustrating my improvement in applied position upon the fingers of the hand of a typist, and 40 Fig. 2 is a greatly enlarged central longitudinal sectional view through the improvement.

In the accompanying drawing the numeral 1 designates a finger shield constructed in 45 accordance with the present invention. The shield includes a sleeve portion 2 which is preferably of a hollow frusto-conical formation and has its reduced end formed with an outwardly extending continuous bead 3. 50 The sleeve 2 may be constructed of any desired material, and is preferably of an elas-

tic nature and the same is provided preferably adjacent its bead 3 with elongated openings 4 arranged in alinement but spaced away from each other. The numeral 5 designates the tip for the shield, the same being of some suitable elastic compressible material and being frustoconical in cross section. The tip 5 upon its inner face is provided with a continuous groove 6 which is adapted 60 to receive the lip 3 of the sleeve 2.

The tip 5 is removable and when worn may be removed and a new tip may be replaced on the sleeve. The device is adapted to promote the speed and efficiency of the 65 typist by relieving her nerves from the bad effect of constant jar by contact with the hard glazed keys of the type machine; by protecting the fingers from injury by such contact and the nature of the tip 5 is such 70 as to prevent the slipping of the fingers of the operator between the keys and the common practice of contacting with more than one key at a desired stroke.

From the above description, taken in connection with the accompanying drawing, the simplicity of the device, as well as the advantages thereof will, it is thought, be perfectly apparent to those skilled in the art to which such invention appertains without 80 further detailed description.

Having thus described the invention, what I claim is:

A finger shield comprising a hollow substantially frusto-conical shell having its 85 sides curved to conform to the curvature of a finger, the smaller end of said shell being provided with an outwardly extending annular bead and being further provided with a plurality of laterally elongated alined 90 openings adjacent said bead, and a removable cup-shaped tip of elastic material disposed upon said smaller end of said shell and provided with an internal groove frictionally engaged upon said bead.

In testimony whereof I affix my signature in presence of two witnesses.

JEAN C. GREGORY.
